DESIGN FOR A TIRE

Elby Edward French, Denver, Colo., assignor to
O. K. Rubber Welding System, Denver, Colo.,
a common law trust

Application June 3, 1944, Serial No. 113,848

Term of patent 14 years

(Cl. D90—20)

To all whom it may concern:

Be it known that I, Elby Edward French, a citizen of the United States, residing at Denver, in the county of Denver and State of Colorado, have invented a new, original, and ornamental Design for a Tire, of which the following is a specification, reference being had to the accompanying drawing, forming part thereof.

In the drawing:

Fig. 1 is a plan view of a portion of a tire, showing my new design;

Fig. 2 is a side view thereof; and

Fig. 3 is a cross-section taken on the line 3—3, Fig. 1.

I claim:

The ornamental design for a tire, as shown.

ELBY EDWARD FRENCH.
